UNITED STATES PATENT OFFICE.

EDWARD V. BURNS, OF CHICAGO, ILLINOIS, ASSIGNOR TO CHICAGO SHIPPING & RECEIPT BOOK COMPANY, A CORPORATION OF ILLINOIS.

LOCKING MEANS FOR LOOSE-LEAF BINDERS.

1,143,359.

Specification of Letters Patent. Patented June 15, 1915.

Application filed February 24, 1913. Serial No. 750,133.

To all whom it may concern:

Be it known that I, EDWARD V. BURNS, a citizen of the United States, and a resident of the city of Chicago, in the county of Cook and State of Illinois, have invented certain new and useful Improvements in Locking Means for Loose-Leaf Binders; and I do hereby declare that the following is a full, clear, and exact description of the same, 10 reference being had to the accompanying drawings, and to the numbers of reference marked thereon, which form a part of this specification.

This invention relates to that class of locking means used in connection with loose leaf binders, for example, of the class sometimes called transfer binders, comprising a binding plate having impaling posts thereon which project through a clamping plate parallel with the binding plate, and on which the leaves of the book are engaged. Such locking mechanisms have assumed many different forms, many of which are complicated and expensive to manufacture, and 20 also, are likely to get out of order or break, when consisting of a number of parts, thus rendering the binder useless until repair.

It is an object of this invention to afford an exceedingly strong locking mechanism 30 whereby the clamping plate is rigidly locked upon the impaling posts and firmly held thereon until released by the operator.

It is also an object of this invention to afford a rocker locking mechanism for each 35 impaling post adapted to be actuated by a sliding member.

It is furthermore an object of this invention to provide means for engaging around the impaling posts to prevent withdrawal of 40 the same from the slots in the clamping plate and the rocker mechanism therein.

It is also an object of this invention to afford loosely engaged rocking mechanisms, which, when moved into one extreme position, serve to bind firmly on an impaling post, and when moved in the opposite extreme position, will permit the impaling post to slide therethrough.

It is also an object of this invention to 50 afford locking means adapted to bind on the impaling post and actuatable by a sliding spring member shiftable on opposite sides of the center of movement of said locking means.

It is also an object of this invention to 55 provide a device in which the rocking, binding mechanisms are pivotally supported on spring plates.

It is finally an object of this invention to 60 provide a device comprising a few number of parts of durable construction, and capable of being cheaply and easily manufactured.

The invention (in a preferred form) is 65 illustrated in the drawings, and hereinafter more fully described.

In the drawings: Figure 1 is a fragmentary top plan view of a loose leaf binder equipped with a device embodying my invention. Fig. 2 is a central longitudinal 70 vertical section therethrough, showing the impaling posts in elevation. Fig. 3 is a plan view of the under side of the cover plate, showing the resilient sliding actuating member. Fig. 4 is a top plan view with the 75 cover plate removed, and showing the rocker elements in plan. Fig. 5 is a fragmentary, enlarged detail section showing one of the rocker elements in release position. Fig. 6 is a similar view showing the rocker ele- 80 ment in locked position. Fig. 7 is a section on line 7—7 of Fig. 4, showing an end elevation of the rocker mechanism in release position. Fig. 8 is a fragmentary view showing the shape of the bearing plate ele- 85 ment.

As shown in the drawings: The reference numeral 1, indicates the binding plate in which are rigidly secured the impaling posts 2.

The numeral 3, designates the clamping plate having the laterally directed slots 4, therein, and each of said plates 1 and 3, is shown as suitably covered with a cloth or fabric 5, which serves to connect said plates 95 with the extended covers of the binder. The cover plate 6, comprises a strip of metal folded over on each of its edges to afford a casing to inclose the working mechanism, and the ends 7, thereof are extended through 100 apertures in the clamping plate and flanged over at 8, thereby securing said casing 6, rigidly upon the same. The upper face or top of said casing 6, is provided with a longitudinal slot 9, and projecting therethrough 105 and secured in the arched sliding spring 10, is the actuating button 11, the amplitude of movement of said spring 10, being limited

by the length of said slot 9. Said sliding spring member or plate 10, is provided at one end with an inwardly directed longitudinal slot, of which the extension 12, of said plate forms one side. Said extension 12, is directed upwardly, the change in curvature thereof from that of the plate 10, occurring at the sharp edged indenture 13. The opposite end of said plate 10, is also slotted to afford the hook member 14, the outer end thereof being caused to bend upwardly, due to a change in curvature effected at the sharp edged indenture 15, similar to the construction described at the opposite end of said plate. Thus it will be seen from the construction described that the plate 10, when detached from the casing normally arches downwardly on each side of the actuating button 11, as shown by the shading in Fig. 3. Beyond the ends of said curvature said plate is reversely bent to cause the extremities to bear upwardly. The resilient plate member 10, when assembled together with the casing on the clamping plate 3, of the binder is held in an upward and flattened position against the cover plate 6, by the rocker elements 16.

The locking or binding members which are adapted to grip the impaling posts 2, consist of the slightly angled strip of metal 16, which is provided on each side thereof, and centrally, with the downwardly extending tongues, which are narrowed at their extremities 17, to afford the downwardly directed bearing faces 18. Said rocking element 16, is provided on one end with the downwardly directed stop 19, which serves to limit the upward movement of that portion on the other side of the center to a substantially horizontal position, which will permit the impaling posts to slide freely through the apertures or slots 20, in said portion of the rocking element. Said rocking element is suitably mounted in the clamping plate 3, with the extremities 17, extending downwardly in apertures in said plate, and the bearing faces 18, resting upon each side of the recesses 21, in bearing plate 22, which lies across and between said apertures in the clamping plate 3. The clamping plate 3, and the cover plate 6, are each provided with the aligned slots 23 and 24, respectively, and the slots 20, in the rocking members are also aligned therewith when said locking members are in release position. Thus it will be seen that when the locking members are in release position the upper cover, and clamping plate 3, of the binder may slide out of engagement with the impaling posts.

The operation is as follows: When the device is assembled the indentures 13 and 15, respectively, of the spring plate 10, bear upon the rocking members 16, and when in the position shown in Fig. 5, the pressure

of the spring being exerted on one side of the center of the rocking member, serves to elevate the same into release position, while on the other hand, when the indenture bears on the other side of said rocking member, as shown in Fig. 6, said member is forced downwardly, thereby causing the sides of the slot 20 to bind or grip upon the impaling post. Said spring sliding plate 10 is provided at each end thereof with the integral extensions 25, which, when the device is in locking position, close across the recesses 24, thus serving to retain the impaling posts within the recesses, and preventing lateral movement of the cover of the binder out of engagement therewith. Thus two locking effects are effected; namely, the one in which the rocking members serve to bind or grip the impaling posts to prevent upward or downward movement thereon, and the closing of the recesses 24, by means of the extensions 25, thus retaining the impaling posts therewithin to prevent transverse movement relative thereto.

I am aware that details of the construction are open to wide variation without departing from the principles of this invention, and I therefore do not purpose limiting the patent granted otherwise than necessitated by the prior art.

I claim as my invention:

1. In a device of the class described pivotally mounted locking members having recesses therein to engage a binding post, a spring plate adapted to actuate the same, and an extension on said spring plate adapted to close across the recesses in said locking members.

2. The combination with the impaling posts of a binder, of spring actuated pivoted locking members having recesses therein adapted to frictionally engage said binding posts, and means adapted to close across the recesses in said locking members to prevent transverse movement relative said impaling posts.

3. The combination with the impaling posts of a binder, of pivoted locking members having recesses therein to permit said binding posts to extend therethrough, and resilient sliding means adapted to bear on opposite sides of the center of said locking members to actuate the same into locking and unlocking position respectively.

4. In a device of the class described the combination with the impaling posts of a binder, of pivotally supported recessed locking members, bearing plates affording support therefor, and a resilient sliding actuating member adapted to bear on said locking members on the opposite sides of said pivoted support therefor to actuate the same into locking and unlocking position respectively.

5. In a device of the class described the

combination with the impaling posts of a binder, of a clamping plate having apertures therein, rocking members having recesses to receive the impaling posts there-through, downwardly extending tongues on said members engaging within the apertures of said clamping plate, a bearing plate lying between the tongues of each of said rocking members to afford a support for said rocking members, and an actuating plate, adapt-

ed to close across the recesses in said rocking members.

In testimony whereof I have hereunto subscribed my name in the presence of two subscribing witnesses.

EDWARD V. BURNS.
